UNITED STATES PATENT OFFICE

159,921

PLAY PEN FOR INFANTS AND CHILDREN

Tyline N. Perry, Denver, Colo.

Application January 10, 1948, Serial No. 143,640

Term of patent 14 years

(Cl. D5—5)

To all whom it may concern:

Be it known that I, Tyline N. Perry, a citizen of the United States, residing in the city and county of Denver, State of Colorado, have invented a new, original, and ornamental Design for Play Pen for Infants and Children, of which the following is a specification, reference being had to the accompanying drawing, forming a part thereof.

The figure is a perspective view of a play pen for infants and children, showing my new design.

I claim:

The ornamental design for a play pen for infants and children, as shown.

TYLINE N. PERRY,
